APPARATUS FOR CONTROLLING FLUIDS IN
OIL WELLS

Roy L. Chenault, Penn Township, Allegheny County, Pa., assignor to Gulf Research & Development Company, Pittsburgh, Pa., a corporation of Delaware

Application March 23, 1939, Serial No. 263,790

9 Claims. (Cl. 103—232)

This invention or discovery relates to apparatus for controlling fluids in oil wells; and it comprises an apparatus for regulation of gas flow and oil flow in oil wells including a tubing means extending from the top of the well down to an intermediate level and tubing means extending from the intermediate level down to a producing horizon, means for anchoring the lower tubing means in the well, a tubular valve sleeve interconnecting 5 said tubing means, in telescopic sliding relation therewith and constructed and arranged to define a gas inlet aperture in conjunction with the lower portion of the upper tubing means and an oil choke aperture in combination with the upper portion of the lower tubing means, the effective areas of which apertures depend on the vertical relation of the sleeve and the two tubing means, and means operable by manipulation of the upper tubing means for adjusting the sleeve vertically with respect to each tubing means; all 10 as more fully hereinafter set forth and as claimed.

In flowing oil wells and in gas lift oil wells, a string of tubing extends from the top of the well to the producing horizon (oil sand), usually with a packer interposed between the tubing and the well above the oil sand. In gas lift or air lift wells, gas or air is admitted under pressure through one or more valves or fixed orifices in the tubing, at intermediate levels to assist in lifting the oil to the well head. For greatest economy of operation the admission of gas should be capable of accurate regulation and moreover the flow of oil through the tubing should be correspondingly regulated to secure a desirable gas-oil ratio in production. The oil flow is ordinarily controlled at the bottom of the tubing by means of a fixed orifice or bottom hole choke restricting flow through the tubing. This expedient is really satisfactory only when it is possible to fit a choke of exactly the right cross-sectional area to the tubing. Fitting the proper choke is a tedious trial-and-error operation because to change a choke the entire string of tubing must be pulled and reset. If the production conditions change a different choke is required.

The main object of the invention is the provision of an apparatus for controlling the gas flow and the oil flow independently from the surface of the well, of exceptionally simple construction and operation. Another object is the provision of an apparatus for independent adjustment of gas flow and oil flow in oil wells in 55 which the two adjustments are made by simply

rotating or raising and lowering the producing string of tubing.

According to the invention the producing string of tubing is divided at some level in the well above the producing horizon, and the lower 5 part of the tubing is anchored in the well and ordinarily is packed off above the producing horizon; though if desired the packer can be omitted. Socket means or the equivalent are provided at the opposite ends of the tubings. A 10 telescopic valve sleeve is arranged to bridge the socket means, forming in effect a sliding tubing section restrained from rotation and the sleeve is so arranged as to provide an upper variable aperture for admission of gas into the tubing 15 and a lower variable aperture for controlling oil flow. The apertures can be formed either by perforations in the sleeve abutting fixed parts of the socket means or tubing or by perforations in the socket means or tubing abutting 20 imperforate parts of the sleeve. The effective aperture of the orifices depends on the vertical positioning of the sleeve with respect to the two socket means. The sleeve is threadedly attached to the upper socket means in such manner that by rotating the upper tubing, the valve sleeve is adjusted vertically with respect to the upper socket means (and incidentally also with respect to the lower socket means), and by raising or lowering the upper tubing without rotation the valve sleeve is adjusted vertically with respect to the lower socket means. Or if desired the threaded connection can be made at the lower socket means. Thus by simple rotary and longitudinal adjustment of the upper string of tubing, at the top of the well, the two apertures can be adjusted independently of each other for any desired rate of flow from zero to maximum.

The apparatus is of simple and rugged construction and, as stated, affords a complete range of adjustment of flow conditions from zero to maximum for both the oil and the gas; this flexibility of adjustment being particularly desirable in wells which are produced intermittently, as is often necessary under proration agreements. Necessity for raising tubing to change orifices is obviated.

In the accompanying drawings there are shown, more or less diagrammatically, six examples of specific embodiments of apparatus within the 50 purview of the invention. In the drawings,

Fig. 1 is a view of the apparatus in elevation, with some parts in section, installed in a well,

Fig. 2 is a view in vertical section of the valve proper of Fig. 1,

Fig. 3 is a sectional view taken along line 3—3 of Fig. 2.

Fig. 4 is a view in vertical section of a modified form of the valve of Fig. 2.

5 Fig. 5 is a view, partly in vertical section and partly in elevation, of a modification wherein the gas orifice and the oil orifice are both provided in the socket means.

10 Fig. 6 is a similar view of a modification in which the sleeve is exterior to the connecting tubings.

Fig. 7 is a similar view of a modified form of the apparatus of Fig. 6 and

15 Fig. 8 is a similar view of a modification where- in threaded adjustment means are provided in the lower socket means.

Referring to the drawings and more particularly to Figs. 1, 2 and 3, the apparatus is shown installed in a well cased at 10 and fitted with a 20 casinghead 11 with inlet 12 for introduction of gas or air under pressure. A string of tubing 13 extends down the well and terminates at some intermediate level (which may be just above the producing horizon) at a socket means comprising 25 a coupler 14 threadedly attached to tubing 13 at 15 and a socket-like sleeve 16 threaded to the coupler at 17. Packing 18 is interposed at the joint between the two sleeves as shown. A lower socket means is provided comprising a socket- 30 like member 20 threaded at 21 to a coupler 22 which in turn is threaded at 23 to a lower string of tubing 24 extending into the producing region of the well. A conventional packer 25 and tubing hanger 26 (omitted from Fig. 2) surround 35 the sleeve 22. The packer seals off the lower part of the well from the upper part and the hanger anchors the lower string of tubing against falling and against rotation. Elements 25 and 26 are of known construction and function and 40 require no detailed description. The apparatus can be installed in an uncased well equally satisfactorily.

The two socket means are bridged by a tubular valve sleeve 30, having a threaded shank 31 en- 45 gaging threads on the inside of sleeve 16. The sleeve makes a snug sliding joint with a collar 32 disposed in sleeve 16 as shown and retained by a threaded cap 33 with interposed packing 34. Lower sleeve 20 has a similar cap 35 and packing 50 36 surrounding the valve sleeve. Additional packing is provided at 37 in sleeve 22. The lower end of valve sleeve 30 has a discoid closure 40, cut away at 41 (Fig. 3) for passage of oil past it and engaging a key 42 integral with the in- 55 terior of sleeve 22 (Figs. 2 and 3). The key prevents rotation of the valve sleeve 30 but permits free vertical movement.

The valve sleeve 30 has an oil orifice 43 in the form of a vertical slot cooperating with the upper 60 part of sleeve 22 and so arranged as to be closed or opened to varying degrees as the valve sleeve is moved up or down. The valve sleeve has a slot-like gas orifice 44 cooperating with cap 33 of the upper socket means in a similar manner. 65 Advantageously but not necessarily a similar but shorter orifice is provided as shown at 45 so that extra orifice area is provided in the full open position of the valve.

The casinghead 11 has an upper socket 46 70 surrounding the upper end of tubing string 13 with interposed packing at 47, and a flange 48 supporting an anti-friction thrust bearing 49. The entire upper tube string is carried on the bearing by nuts 50 and 51 engaging threads 52 75 cut for several inches along the upper end of the

tubing. The bearing and the nuts are made of substantial construction and of adequate size to carry the load.

In operation the course of gas and oil through the apparatus is as shown in Figs. 1 and 2. If it is desired to change the oil orifice setting without affecting the gas orifice setting, the procedure is to retain the upper part 53 of the tubing string against rotation by means of wrench or tongs (not shown) applied to part 53, loosen 10 nut 51 from nut 50 and screw the nut 50 to raise or lower the upper tubing string. This moves the valve sleeve 30 with respect to the lower socket means and varies the exposed area of orifice 43. The nut 50 is then locked with nut 15 51. To change the gas orifice setting, nuts 50 and 51 are turned by the wrench, which rotates the upper tubing string without moving it up or down, and thereby screws valve sleeve 30 up or down to expose different areas of orifice 44. This 20 adjustment simultaneously changes the setting of orifice 43, so when orifice 44 is adjusted to the desired position, orifice 43 is brought back to its initial position by raising or lowering the upper string of tubing as described. The gas orifice and 25 the oil orifice can be set independently to any desired position between zero and full open.

In the apparatus of Figs. 1, 2 and 3 raising the upper string of tubing closes the oil orifice 43. It is sometimes more convenient to arrange 30 for raising of the upper tubing to open the oil orifice, and such modification is shown in Fig. 4. An inner sleeve 60 is provided, threadedly attached at 61 to the upper end of the lower tubing and making a sliding joint with the interior 35 of a valve sleeve 130, which has a lower flange 62 engaging the interior of sleeve 22 and containing annular packing 63 engaging sleeve 60. Flange 62 engages key 42 to prevent rotation of sleeve 130. The flange clears member 22 sufficiently to prevent entrapment of oil above the flange. Sleeve 60 has a solid central portion 64 and is slotted below the central portion at 65 for free passage of oil. Sleeve 60 has a slot 66 serving a function similar to slot 43 in Fig. 2. The 45 rest of the apparatus of Fig. 4 is like that of Figs. 1 and 2.

In operation, upon raising the upper tubing string a greater area of slot 66 is exposed, and vice versa; just the reverse of Figs. 1 and 2. 50

While the forms of the invention shown are particularly advantageous working embodiments, the invention can be modified as to form without affecting the ultimate result: independent regulation of the gas and oil flows by rotary and longitudinal manipulation of the tubing string at the top of the well. Figs. 5, 6, 7 and 8 show modified constructions each having utility in particular cases.

Fig. 5 shows a form of the invention like that 60 of Fig. 4 except that the oil aperture is also formed in the socket means in lieu of in the sleeve itself. Thus, an upper socket means 70 is provided, attached through a reducer 71 to the upper tubing string 13, and threadedly engaging at 72 65 the upper portion of an imperforate sleeve 73. A gas orifice 74 of vertically elongated shape is provided in the socket means registering with the upper end of the valve sleeve as shown to provide a variable throttling orifice. Packing 75 is inter- 70 posed around the sleeve as shown. The lower oil valve is exactly like that of Fig. 4 and requires no description.

In operation, rotary adjustment of the upper tubing adjusts the gas orifice, and translatory 75

adjustment of the tubing adjusts the oil orifice, as is apparent from the drawing.

In Fig. 6 the sleeve is an exterior sleeve and thus no socket means are required. The sleeve 78 slidingly engages a tubing section 79 attached by an ordinary coupling 80 to the upper tubing string 13, with interposed packing 81, and slidingly engages the upper end of the lower string of tubing 124, with interposed packing 82; the upper end of the tubing being flanged at 83 to allow the lower tubing to be raised when the apparatus is withdrawn from the well. The upper end of the tubing also carries a key-way 84. Tubing member 79 carries a male-threaded flange 85 engaging threads 86 on the interior of the sleeve, as shown, and has a slot-like orifice 87 registering with the upper termination of the sleeve, as shown, to define a variable gas orifice. The oil orifice is defined by a slot 88 in a short sleeve extension 89 fixed to the valve sleeve by a disk 90, perforated around its outer rim at 91 to allow free passage of oil. The slot registers with the top of tubing 124 to define a variable oil choke. Extension 89 has an integral key 92 registering with key-way 84 to prevent rotation of the sleeve with respect to the lower tubing.

The operation of the device of Fig. 6 is deemed apparent from the drawing in view of the preceding descriptions.

In Fig. 7, a valve sleeve 95 makes a threaded connection with a flange 96 on the lower end of a tubing extension 97 coupled to the upper string of tubing 13, in a manner similar to the arrangement of Fig. 6. A gas orifice is defined by an opening 98 in the body of the sleeve registering with the lower end of the extension 97 as shown. The lower portion 99 of the sleeve is in telescopically sliding relation to a socket member 100, similar to that of Fig. 2 and including an enlarged cylindrical cavity 101, and an integral key 102 engaging a cap 103 on the lower end of sleeve portion 99. The socket member is attached at 104 to the lower tubing 24. A slot 105 in sleeve portion 99 defines an oil choke orifice 45 as shown.

In Fig. 8, the threaded adjusting means are in the lower socket member rather than in the upper member as shown in previous figures. The valve sleeve 110, orificed at 109 for gas, extends 50 into an upper socket member 111 attached at 112 to the upper tubing string 13, and having an integral key 113 engaging a flange 114 on the valve sleeve, to prevent rotation thereof. The lower end of the sleeve extends into a lower socket member 115 and has a threaded flange 116 engaging threads 117 on the inside of the socket member. Packing 118 in the flange makes a leakage resistant joint with a short tubular extension 119 within the socket member as 55 shown. The extension 119 is orificed at 120, to define a variable aperture oil choke, and has a partition 121, below which is an opening 122 to permit flow of oil as indicated by arrows.

The operation of the apparatus of Fig. 8 is 60 like that of the other modifications and requires no description.

Provision of a packer in combination with the apparatus described is ordinarily desirable only when the working fluid level is somewhere near 65 the lower end (not shown) of the lower tubing 24. In this case unless a packer is used there would be danger of admitting gas directly around the lower end of the tubing which would nullify the advantage of having the small adjustable gas orifice farther up the tubing to permit accurate

control of gas entry. But in many cases the operating oil level may be several hundred feet above the lower end of lower tubing 24 so that there would be no danger of gas breaking over the lower end of the tubing, with normal fluctuations in operating pressure. The gas orifice is always located considerably above the operating fluid level. In many cases it is advantageous from the standpoint of flowing efficiency to permit formation gas to separate from the oil and accumulate in the annular space between tubing and casing, and then readmit this gas to the tubing at a higher level. In such event the packer is omitted. Fig. 8 shows the apparatus installed merely with the tubing hanger 26; no packer being provided, and the same arrangement can be employed with the other embodiments of the invention.

The apparatus is embodied in the usual materials for oil well fittings. The several parts are of simple form and are readily produced by simple turning and machining operations. The entire apparatus can be set in position in the well, and pulled out of the well, as a unit. Operation is simple and effective.

What I claim is:

1. In apparatus for regulation of fluid flows in oil wells and including a tubing means extending from the top of the well down to an intermediate level, tubing means extending from the intermediate level down to a producing horizon and means for anchoring the lower tubing means in the well, the improvement comprising a tubular sleeve connecting both said tubing means in telescopic sliding relation therewith and constructed and arranged to define a gas inlet aperture in combination with the lower portion of the upper tubing means and an oil choke aperture in combination with the upper portion of the lower tubing means, the effective areas of said apertures depending on the vertical relation of the sleeve and the two tubing means, and means operable by manipulation of the upper tubing means for adjusting the sleeve vertically with respect to each tubing means.

2. The apparatus of claim 1 wherein the tubular sleeve is perforated in the lower part thereof adjacent the upper termination of the lower tubing means and is perforated adjacent the lower termination of the upper tubing means, whereby to provide said inlet aperture and oil choke aperture respectively.

3. The apparatus of claim 1 wherein the tubular sleeve is perforated adjacent the lower termination of the upper tubing means to provide said gas inlet aperture, and the lower tubing means contains a fixed perforated sleeve registering with the valve sleeve to provide the oil choke aperture within the lower tubing means.

4. The apparatus of claim 1 wherein the means for adjusting the sleeve vertically comprises nut means on the sleeve cooperating with screw threads within the upper tubing means so that upon rotation of the upper tubing means the sleeve is caused to protrude various distances from the upper tubing means, and means are provided in the lower tubing means for preventing rotation of the sleeve.

5. An apparatus for regulation of fluid flows in oil wells and including an upper string of tubing 70 extending from the top of the well down to an intermediate level, lower tubing extending from the intermediate level down to a producing level, means for anchoring the lower tubing in the well, a socket attached to the lower end of the upper

tubing, a socket attached to the upper end of the lower tubing, a valve sleeve bridging the sockets and in telescopic sliding relation therewith, means in the lower socket for preventing 5 rotary movement of the sleeve while permitting longitudinal movement thereof, threaded means operably connecting the upper socket and the sleeve whereby upon rotation of the socket the sleeve is caused to protrude to various degrees 10 therefrom, the sleeve being orificed adjacent the lower end of the upper socket to provide a variable gas inlet to the tubing, and being constructed and arranged to define a variable oil orifice in the lower socket the effective area of which depends 15 on the vertical position of the sleeve with respect to the lower socket.

6. An apparatus for regulation of gas flow and oil flow in wells comprising an upper tubing extending down in the well to an intermediate level, 20 upper sleeve-holding means attached to the lower end of said tubing, lower sleeve-holding means in communication with an oil horizon, means for anchoring the lower sleeve-holding means in the well, a tubular sleeve engaged at its opposite 25 ends by said sleeve-holding means and in vertically adjustable relation with respect thereto, said sleeve in relation with the upper sleeve-holding means being constructed and arranged to establish aperture communication with the 30 well and the interior of said upper tubing member, which aperture is uncovered to a varying extent depending on the vertical movement of said sleeve, the said sleeve further being arranged with respect to its lower holding means 35 to establish a throttling aperture within the lower holding means uncovered to a varying extent dependent on the vertical movement of the said sleeve, and means associated with said sleeve and one of said holding means for adjusting the 40 sleeve vertically with respect to the holding means.

7. An apparatus for regulation of gas flow and oil flow in oil wells comprising an upper tubing extending from the top of the well down to an intermediate level, an upper sleeve holding socket 45 means attached to the lower end of the tubing, a

lower sleeve holding socket means in communication with an oil horizon, means for anchoring the lower sleeve holding means in the well, a tubular valve sleeve engaged at its opposite ends by said sleeve holding means, and in vertically 5 adjustable relation with respect to them, said valve sleeve in conjunction with the upper sleeve holding socket means being constructed and arranged to establish an aperture communicating with the well and the interior of the sleeve and 10 uncovered to a varying extent dependent on the vertical movement of the sleeve, and cooperating with the lower sleeve holding socket means to establish a throttling aperture within the socket means, uncovered to a varying extent dependent 15 on the vertical movement of the sleeve, screw means connecting the valve sleeve and the upper socket means constructed and arranged so that rotation of the upper socket means causes vertical movement of the sleeve with respect thereto, and means for rotating the upper tubing and raising and lowering it whereby to vary said effective aperture areas.

8. The apparatus of claim 7 wherein the sleeve is orificed at a point adjacent the lower termination of said upper socket means so that different effective areas of the orifice are uncovered in vertical adjustment of the sleeve, whereby to define said first named aperture, and is orificed at a point within the lower socket means so that 25 different effective areas of said second orifice are uncovered in vertical adjustment of the sleeve whereby to define said second named aperture.

9. The apparatus of claim 7 wherein the sleeve 30 is orificed at a point adjacent the lower termination of said upper socket means so that different effective areas of the orifice are uncovered during vertical adjustment of the sleeve, whereby to define said first-named aperture, and an orificed 35 fixed tube is provided in the lower socket means adapted to be uncovered to different degrees by the sleeve, whereby to define said second named aperture.

ROY L. CHENAULT. 45
